UNITED STATES PATENT OFFICE.

HENRY DE HUFF, OF CYNWYD, PENNSYLVANIA, ASSIGNOR TO D'OLIER CENTRIFUGAL PUMP AND MACHINE COMPANY, OF PHILADELPHIA, PENNSYLVANIA, A CORPORATION OF PENNSYLVANIA.

PUMP CONSTRUCTION.

1,107,591.

Specification of Letters Patent. Patented Aug. 18, 1914.

Application filed May 17, 1913. Serial No. 768,354.

To all whom it may concern:

Be it known that I, HENRY DE HUFF, a citizen of the United States, residing in Cynwyd, in the county of Montgomery and State of Pennsylvania, have invented certain new and useful Improvements in Pump Construction, of which the following is a specification.

- My invention relates to the construction 10 of a centrifugal pump and more particularly to the construction of such a pump which is of unusual size as when required to lift or move extremely large quantities of water or liquid.
- 15 My invention resides in a centrifugal pump in which one or more of the stationary parts, such as the pump case or discharge casing, suction heads, etc. are made of plain concrete or reinforced concrete.
- 20 My invention resides in the features of construction hereinafter described and claimed.

For an illustration of some of many forms my invention may take reference is to be had 25 to the accompanying drawings, in which:

Figure 1 is a vertical sectional view, some parts in elevation, of a double suction pump embodying my invention. Fig. 1^a is a fragmentary view on a larger scale of a part of 30 the section of Fig. 1, some parts shown in elevation. Fig. 2 is an end elevational view of the pump shown in Fig. 1, partially in section, parts broken away to show internal construction. Fig. 3 is a side elevational 35 view of a single suction pump embodying my invention, some parts broken away and some shown in section, the suction head in this case being in a single piece concrete construction. Fig. 3^a is a sectional view of 40 part of the construction illustrated in Figs. 1 and 3, some parts in elevation. Fig. 3^b is a cross sectional view of a part shown in Fig. 3^a. Fig. 4 is a side elevational view, parts broken away and parts in section, of a 45 pump in which the discharge or pump casing and the suction head are divided along a horizontal plane, the suction head pump casing parts being integral or cast of concrete in one piece. Fig. 5 is a side elevational view, parts broken away and parts in 50 section, of a double suction pump with the

suction heads cast separately and divided along a horizontal plane. Fig. 6 is a side elevational view, parts broken away and parts shown in section, of a double suction 55 pump in which the suction heads are of reinforced concrete cast integral with the pump or discharge casing, the suction head and casing being divided along a horizontal plane. Fig. 7 is a vertical sectional view, 60 some parts in elevation, of a vertical single suction pump. Fig. 7^a is a sectional view, on larger scale, of a construction similar to that shown in Fig. 3^a. Fig. 8 is a side elevational view, parts broken away and parts 65 shown in section, showing a pump case or discharge casing in a single piece with a suction head divided along a horizontal plane, the suction head parts made of reinforced concrete.

70 Referring to Figs. 1, 1^a and 2, S represents a shaft having a suitable bearing as b supported upon any suitable part such as a pump base or separate foundation, it being understood that the shaft S is driven by belt, 75 direct connection to motor, or by any other suitable means for rotating at the desired speed the runner or impeller I secured upon the shaft S. The impeller I has a suction opening s at each end, the outer periphery 80 or discharge point of the impeller being indicated at d. The liquid or water discharged by the impeller passes into the pump case or discharge casing D having the final discharge orifice D^o indicated in Fig. 2, the 85 casing D being here shown as of involute form. This discharge casing D is made of concrete, cement or other suitable material which may be molded or worked into the form desired and which then takes a set and becomes rigid. In the case here illustrated the concrete is reinforced. At each side of the discharge casing and at its portion next to the impeller is the annular ring R, here shown of channel or U section, such rings 90 being made preferably of cast iron, and preferably circumferentially continuous, though they may be circumferentially segmental. At suitable distances circumferentially of each ring R may be provided a 100 transversely extending bar or member a. A transversely extending reinforcing rod r of

iron or the like is attached at one end to one of the bars *a* and at its other end to the bar *a* in the other ring *R*, this attachment to the bar *a* being by any suitable construction, such as a hook *h* at each end of the bar *r*. It will be understood that these reinforcing bars are re-current around the circumference of the casing *D*, and change in length and shape to suit the cross section necessary for an involute casing. And extending circumferentially of the casing *D*, that is, substantially at right angles to the bars *r* are the numerous reinforcing rods *c*, it being understood that the rods *r* and *c* are completely embedded within the concrete *C* forming casing *D* for reinforcing purposes. The circumferentially extending rods *c* may be fastened at one end to the flange *f* on the case end plate *e* at the discharge orifice *D'*, Fig. 2, any suitable conduit for conducting the discharged liquid or water being bolted or otherwise secured to the flange ring *e*. Spacing or separator members *g* may be disposed between two rings *R*, suitable bolts drawing the two rings *R* toward each other against the members *g*. Or these members *g* may be cast integral with and thus join the rings *R*. And these members *g* may be so shaped and positioned as to constitute guide vanes, it being understood that the vanes or members *g* recur at suitable points around the discharge orifice of the impeller *I*. The lower portion of the casing *D* may be set in or cast integral with a foundation block *F* which may also be of concrete, this member *F* supporting the casing *D* and attached parts. Secured by bolts *j* to the rings *R* are the two suction heads *H* here shown as of metal, such as cast iron. Each suction head is shown as having the flange or rib extending under a ring *R*, and each head is further provided with the stepped portions *m* with which the impeller *I*, similarly stepped, has a running fit. And each suction head *H* has a gland or stuffing box *n* making a running water tight fit with the shaft *S*.

In Fig. 1^a the concrete of the casing *D* is represented at *C*. In Fig. 3 is shown a single suction pump in which the casing *D* is of substantially the construction described in connection with Fig. 1. In this case however the suction head *H* is made in one piece of reinforced concrete, having longitudinally extending reinforcing rods *o* and the circumferential rods *p*. At the inner end of the suction head *H* is the head *q*, preferably of cast iron, held by bolts *j* to the ring *R* and having the stepped running fit *m* with the impeller *I*, it being understood that the member *q* is cast in the concrete of the head *H*. At the other end of the impeller is a cast iron head *H'* held by bolts *j* to the left hand

ring *R*, the shaft *S* extending through the stuffing box or gland *n'* in the head *H'*.

In Fig. 3^a is shown the construction of the rings *R* and mode of attachment of reinforcing rods *r*, etc., as shown in Fig. 1^a, and being of construction suitable to either Figs. 70 or 3, or others. As shown in Fig. 3^b the member *g* is of a section suitable for operating as a guide vane as previously described.

In Fig. 4 the pump or discharge casing *D* is divided along the horizontal plane *t*, the flanges secured together by bolts *j'*. Here the suction head *H* is also of reinforced concrete as described in connection with Fig. 3 but is divided along the horizontal plane *t* and provided with flanges held together by bolts *j'*. In place of the end flange *q* and the ring *R* of Fig. 3, the member *n*, preferably of cast iron, is provided, its inner end taking the place of one of the rings *R* providing means for attachment of reinforcing rods *r* and at its other end in the suction head *H* providing means for attachment of reinforcing rods *o*, and a stepped running fit being provided for the impeller *I*.

In Fig. 5 a construction is shown involving the single piece discharge casing *D* similar to that described in Fig. 1. Two suction heads are here shown divided along a horizontal plane and secured by bolts *j* to the rings *R*. In the casing *D* may be provided the man hole ring *v*, as of sheet or cast metal cast in the concrete *C*, the reinforcing rods *r* at this point being interrupted and connected to the ring *v*. An airtight cover *v'* is secured to the ring *v*, the removal of the cover *v'* uncovering the opening through which a man may enter into the casing *D* for the purposes of inspection, cleaning, repair, etc. In Fig. 5, as in Fig. 4, the gland or stuffing box *n* may be divided along a horizontal plane and may have means for attachment of the reinforcing rods *o* as indicated in Fig. 5.

In Fig. 6 a double suction pump is shown with both the suction heads and the casing *D* divided along the horizontal plane, the suction head parts being cast integral with the casing parts as described in connection with Fig. 4. In this case a ring member *w*, preferably of cast metal, is cast in the concrete *C* of the casing *D* to form a priming connection, that is, a hole or connection through which liquid or water may be supplied to fill the pump to prime it at starting.

In Fig. 7 is shown a vertical pump, that is the shaft *S* is vertical. Here the discharge casing *D* of reinforced concrete *C* may be made integral with the concrete base *F* through which extends the suction passage *F'*. Here the head *H'* is secured by bolts *j* to the upper ring member *R*, while the lower

member R has the extending flange R^a with which the impeller I has a running fit.

In Fig. 7^a the rings R, similar to those described in connection with Figs. 1^a and 5 3^a are spaced apart by the separators g, which may act simply as separators, or as 10 separators and guide vanes, as above described. In this case the member g has the terminal extensions x extending through the ring members R and receiving at their ends the nuts y. This construction is to be understood as an alternative for any of the pumps.

In Fig. 8 a horizontal pump is shown 15 with a separate suction head H, made of reinforced concrete, and divided along the horizontal plane t. In this case there is on the head H the cast flange member z bolted to the ring member R and providing a 20 running fit with the impeller I.

It is to be understood that in place of the reinforcing rods and means illustrated, any other reinforcing means may be employed such as sheets or plates of iron or the like, 25 which latter also assists in making the concrete members water tight.

The concrete parts, as pump casing and suction heads, etc., may be water proofed by any suitable means, as by incorporating 30 the same within the body of the cast concrete, as when one or more layers of asphalted paper or fabric is employed; or by mixing with the concrete before casting any suitable water proofing preparation; or by 35 applying a water proofing preparation to the concrete after casting.

What I claim is:

1. The combination with a centrifugal pump casing of concrete or the like, of an 40 annular metallic member attached to said casing and forming the inner boundary of said casing at the impeller bore thereof.

2. An involute pump casing of concrete or the like, and reinforcing members in the 45 concrete of said casing and conforming to the involute shape of said casing.

3. An involute pump casing of concrete or the like, reinforcing members in the concrete of said casing and conforming to the 50 involute shape of said casing, and reinforcing members in the concrete of said casing extending transversely thereof.

4. A centrifugal pump casing of concrete or the like, said casing having a bore, and 55 metallic members attached to the concrete of said casing at its edges next to said bore.

5. A centrifugal pump casing of concrete or the like, said casing having a bore, metallic members attached to the concrete of said 60 casing at its edges next to said bore, and reinforcing members in said concrete attached to said metallic members and extending transversely of said casing.

6. The combination with the casing of a

centrifugal pump, of a metallic member at 65 the bore of said casing, a suction head of concrete or the like, a metallic connecting flange at the end of said suction head, and means securing said metallic connecting flange to said metallic member.

7. The combination with the casing of a centrifugal pump of concrete or the like, of a metallic member at the bore of said casing, 70 a suction head of concrete or the like, a metallic connecting flange at the end of said suction head, and means securing said metallic connecting flange to said metallic member.

8. The combination with a centrifugal pump casing of concrete or the like, metallic 80 rings forming the ends of the casing section, and a strut extending between said rings.

9. The combination with a centrifugal pump casing of concrete or the like, metallic 85 rings forming the ends of the casing section, and a strut extending between said rings, said strut constituting a guide vane.

10. The combination with a centrifugal pump casing of concrete or the like, of an annular ring forming a shoe for each inner 90 edge of said casing, and a plurality of struts disposed between said rings at a plurality of recurring points.

11. The combination with a centrifugal pump casing of concrete or the like, of an 95 annular ring forming a shoe for each inner edge of said casing, and a plurality of struts disposed between said rings at a plurality of recurring points, said struts forming guide vanes.

12. The combination with a centrifugal pump casing of concrete or the like, of an annular metallic shoe for the inner edge of 100 said casing, a suction head, means for securing said suction head to said shoe, and an impeller having a running fit with said connecting means.

13. The combination with a centrifugal pump casing of concrete or the like, of a metallic shoe of channel or U section for 110 each inner edge of said casing, the concrete of said casing extending into said shoe.

14. A centrifugal pump casing of concrete or the like, said casing divided into sections, and coöperating attaching flanges 115 for said sections, each flange attached to the concrete of its section.

15. The combination with a centrifugal pump casing, of a suction head of concrete or the like, said suction head divided into 120 sections, said sections having flanges, for connecting said sections together, each flange connected with the concrete of its section, and means connected with the concrete of the suction head sections secured to said 125 pump casing.

16. The combination with a centrifugal pump casing of concrete or the like, of a

foundation cast integral with a part of said pump casing.

17. The combination with a suction head of concrete or the like, of a shaft gland or stuffing box having members attached to the concrete of said head.

In testimony whereof I have hereunto

affixed my signature in the presence of the two subscribing witnesses.

HENRY DE HUFF.
